[57] ABSTRACT

To avoid spillage of a potential contaminant normally fluid at ambient temperatures, a tanker used for transportation of such fluid will be so built and so operated

that the cargo will be chilled to a temperature below the point at which it will congeal. Petroleum is an example of such a fluid. Before delivery, the petroleum or other cargo is to be raised to a temperature at which it is again fluid and can be pumped from the storage tanks in which it has been transported. From a method standpoint, a series of tankers can be served by a single high capacity refrigeration device at the port of embarkation, each tanker requiring, therefore, only minimum refrigeration equipment to maintain the paraffin-congealing temperature during transit. Similarly a single high capacity heating system will serve a succession of tankers to restore the contents to fluidity as a port of debarkation.

By way of example, the cargo is assumed to comprise petroleum such as crude oil. Most hydrocarbon oils contain substantial quantities of paraffin and may, therefore, be congealed. In the case of crude oil, the temperature below which the oil cannot be poured will ordinarily range no lower than -70°F. Most are well above that temperature. A text book gives the pour point of Pennsylvania crude oil at 4°F. The pour points given for Oklahoma, Colorado and certain Texas-Louisiana oils are 5°F. Many other crudes will congeal at -15 or -20. Some even congeal at temperatures of 90°F. or higher.

REFRIGERATION TO AVOID CONTAMINATION BY A HYDROCARBON

CROSS REFERENCE TO PREVIOUS APPLICATION

This application is a companion to my co-pending application Ser. No. 113,328, filed Feb. 8, 1971, for an Ice-Channel Cutting Attachment for Ships.

BACKGROUND OF INVENTION

Great concern has resulted from numerous incidents in which damage to the hulls of tankers has resulted in the escape of petroleum and resulting contamination. This invention is based on the fact that all petroleum, and many other products, contain paraffins and the like which can be congealed to immobilize crude oil at temperatures which usually are not as low as, and no lower than, -70°F.

SUMMARY OF INVENTION

In terms of apparatus and method, the invention contemplates transportation of crude oil and other like products in congealed form so that the liquid cargo will not escape from the transporting tanker even if the hull of the tanker is damaged. The refrigerating mechanism may, in some embodiments, comprise cooling coils at or near an insulated tanker wall, and which coils constitute the evaporator of a refrigeration system. The refrigerant lines or coils may be so placed as to allow for the necessary cooling throughout the cargo so that at the time of embarking the entire cargo is congealed. As the oil or the like is loaded it immediately begins undergoing the cooling process. Any section or compartment of the ship can be controlled separately. This separate manual or automatic tank control enables the oil or product in the immediate vicinity or in adjacent tanks near a puncture or break in the ship's hull to be still refrigerated in spite of the failure. The continued cooling in such an event will prevent the oil from entering the water. Normally with a hull failure or puncture the oil contained in the damaged tank immediately flows out of the confines of the ship and is soon spread over a large surface of water, and any action to restrain the oil is accomplished after the spill. In this invention the spill is prevented from occurring or, at least in a very major break, due to the state of the oil there is time to act to restrain whatever oil might begin to move from its tank.

If the crude oil cargo had been congealed before the carrier leaves port, it will not escape even if the hull is accidentally punctured or broken. The cargo will tend to remain gelatinous or like a chunk of paraffin. Lake or sea water freezing on the oil because of its low temperature would act as insulation and as a secondary hull. Since the refrigeration requirements during transport are greatly reduced after the desired low temperature has once been attained, it is only necessary to provide modest refrigerating capacity on the individual ships.

The method can be practiced without substantial refrigeration if, in lieu thereof, or as a supplement thereto, a congealing component such as paraffin, which is normally congealed at ambient temperature, is introduced into the oil or fuel which constitutes the prime cargo.

By the same token, the heating mechanism required to restore the petroleum to fluidity can serve a whole succession of ships at a port of debarkation.

Additional features of the invention include: (a) introducing bubbles of gas along the side walls of the tanker (b) minimizing wave motion within the tanker by congealing the cargo and (c) using either or both a reduced temperature or a congealing additive to congeal the cargo and to keep the cargo congealed.

BRIEF DESCRIPTION OF DRAWINGS

FIG. 1 is a diagrammatic cross section through a hull 10 made in accordance with this invention for transportation of petroleum and the like in congealed form.

FIG. 2 is a view in end elevation showing a ship hull moored to a wharf having large capacity refrigeration and/or heating mechanism to serve a succession of such hulls.

FIG. 3 is a fragmentary diagrammatic external view showing a portion of a hull equipped with an encircling pipe for discharging air bubbles which, floating up the side of the hull, will prevent the freezing of ice on the hull surface.

DETAILED DESCRIPTION

The hull 10 per se may be of any appropriate construction. Preferably it will be divided by partitions 11. 25 The present invention contemplates that it will have interior insulation at 12 which may be foam or sheet or other insulation adherent adhesively or otherwise to the interior of the hull. Normally, in immediate proximity to the insulation 12, there will be a refrigeration coil 14 which may comprise one or more convolutions in endless series. I use the term "endless series" to indicate that the refrigeration coil 14 is in series connection through pipe 16 with a condenser diagrammatically illustrated at 18 and to which refrigerant is supplied by compressor 20, the compressor having an intake pipe 22 in series connection with the other expansion end line 14 and connected by pipe 24 to deliver the compressed refrigerant to the condenser 18, whereby one well-known type of refrigerating system is in series with the expansion coil 14 which absorbs heat to be rejected from the condenser.

It is conventional in many refrigeration systems not to use the refrigerant directly for the ultimate cooling task. Accordingly, the method herein disclosed contemplates the possibility that the refrigerating system may chill a circulatory current of low freezing point liquid which will then pass through the refrigeration coils to cool the cargo.

While FIG. 1 shows the refrigerating mechanism directly mounted on deck 32 of the hull 10, and while refrigerating mechanism of modest capacity is required to maintain the congealed state of the cargo during transportation, it is preferred that the initial chilling of the cargo to congeal the crude oil or other material should be done by a large capacity refrigeration system such as that diagrammatically illustrated at 34 in FIG. 2. It is connected to the space or coils provided in the hull for the refrigerant. On the same wharf or on a like wharf at a delivery point, a large scale heating plant may be provided as shown at 38, the arrangement being such that this will deliver a gas or highly heated liquid through the pipe 40 into the coils 14, or parallel coils, or other space for heating fluid in the interior of the hull.

Since the hull diagrammatically shown in FIG. 1 at 10 may be operating in channels 56 through ice floes 58, and since the hull itself will unavoidably tend to absorb

heat by virtue of the refrigeration of the coils 14 or convection spaces 52 which are present, it is desirable to provide means for preventing the hull from becoming frozen in ice, particularly during a period in which it may be at rest. To this end, pipe 60 encircling the hull well below the level at which the water 62 is frozen is supplied with air through any appropriate compressor. The pipe has a series of discharge openings 64 which are preferably directed downwardly and inwardly toward the hull to release air bubbles such as those shown at 66. These bubbles rising beside the hull tend to carry upwardly along the hull surface water which is warmer than that of the surface and which, both by reason of its temperature and its motion will tend to keep ice from freezing on the surface of the hull. The perforated compressed air line around a refrigerated tanker ship may be supplied with air heated due to the process of compression of the refrigerant in condenser 18 or otherwise. It being understood that the whole mechanical disclosure is diagrammatic, I have shown on a diagrammatic basis, a motor-driven compressor 68 having an output pipe 70 communicating with the pipe 60 for delivering air to the latter.

In terms of method, it is quite immaterial precisely how the cargo of crude oil or the like is refrigerated. Above suggested are arrangements for:

1. Passing compressible refrigerant from a condenser to one or more sets of convolutions of one or more evaporator coils to which the cargo is exposed in heat conductive relation.

2. Using conventional refrigeration machinery to chill a non-freezing liquid which can be circulated through such coils to absorb heat from the cargo.

3. Since, as the temperature decreases, the viscosity of the crude oil increases due to the paraffins separating out as waxy solids, another aspect of the invention would be to add paraffin or other high melting point solids to the crude oil at the port of embarkation and thereby bring about the congealing of the crude oil with a less reduction in temperature. This extra paraffin can either be brought by the receiving ship itself or be stored at the port prior to being heated and added to the oil. Later this high melting point solid can be removed at a refinery or other appropriate location and can be reused, if desired, for the same purpose.

In all of these arrangements, the essential feature consists in handling transportation in whole or principal part while the cargo is congealed.

It is also true, of course, that a liquid of any type used as an anti-freeze liquid in an automobile radiator, or such a well-known refrigerant as ammonia, may be employed to reduce the temperature of the crude oil or like cargo to the points where its paraffin content causes it to congeal. The circulatory fluid used to reheat the oil above its pour point will desirably comprise either ammonia or ethylene glycol. It is desirable for the same fluid to be used for both processes so as to eliminate the necessity of two pipe systems or the draining of the lines for the changeover.

The congealed state of the cargo eliminates the problems of stability with tanker ships due to the free surface otherwise found with liquid cargo, for, for, as the ship is heeled, the liquid surface tends to remain horizontal. Also related to ship stability (and again eliminated) is free communication with the sea such as occurs when a liquid cargo flows from a fractured or

punctured tank thereby allowing sea or lake water to flow freely in or out of the damaged compartment.

Great advantages are perceived in using heavy duty refrigeration equipment which functions successively on several carriers of this type, thus making it unnecessary for the individual carrier to be equipped with refrigerating mechanism other than just sufficient to maintain the cargo congealed during transport.

I claim:

- 10 1. A method of avoiding ecological contamination by accidental release during transporting of a potential petroleum contaminant which is normally liquid at ambient temperatures, such method consisting in providing a vessel with a storage container with a refrigeration coil in the container for heat exchange contact with the petroleum and providing a source of refrigerant on the vessel for circulation through said coil, filling the container with the liquid to be transported, reducing the temperature of such liquid below the point at which it 15 congeals by circulating a refrigerant through said coil, transporting the container and liquid while congealed, and raising the temperature of the congealed container contents to restore the potential contaminant to a liquid state for removal from the container at the point of debarkation.
- 20 2. A method according to claim 1 which includes providing a dockside source of refrigerant, making a massive reduction in the temperature of the potential contaminant fluid before embarking by connection of said coil to a dockside source of refrigerant and thereafter keeping it only sufficiently cool to maintain the congealing thereof by use of the refrigerant source on the vessel.
- 25 3. A method according to claim 1 including the step of causing the congealing of the fluid by adding a congealing component thereto.
- 30 4. A method according to claim 1 in which the point of debarkation is provided with a source of heated fluid and the petroleum is raised in temperature by connection of the coil to the source of heated fluid and circulating heated fluid through the coil to restore it to liquidity.
- 35 5. A method according to claim 2 in which the potential contaminant is a hydrocarbon oil containing paraffin.
- 40 6. A method according to claim 1 in which the said petroleum contains paraffin and in which the petroleum is lowered in temperature to a value materially below the pour point of said petroleum.
- 45 7. A method according to claim 1 in which the liquid to be transported is introduced into a carrier and the step of reducing its temperature is performed successively on a series of such carriers, the step of maintaining the temperature of the liquid below the pour point during transportation being performed separately on respective carriers.
- 50 8. A method according to claim 7 in which the step of modifying the temperature is performed by means not transported by the carrier.
- 55 9. A method according to claim 7 in which the temperature of the fluid to be transported is modified on a large scale in port and is only changed on a small scale while in transit.
- 60 10. A method according to claim 1 in which the carrier is a vessel and a compressed fluid is released into the carrier-supporting water externally about the vessel to prevent the vessel hull from becoming frozen in ice.

11. A method of avoiding ecological contamination by accidental release during transporting of a hydrocarbon which is normally fluid at ambient temperatures, said method consisting of congealing the fluid by add-

ing paraffin and reducing the temperature of such fluid below the point at which it congeals and transporting the fluid while congealed.
